[57]

ABSTRACT

A transistor amplifying circuit having an amplifying transistor, a biasing transistor and an emitter follower transistor. The emitter follower is interposed between the signal source and the amplifying transistor to increase the input impedance of the circuit. Temperature compensating means are provided, and in one embodiment, a current sink is provided to increase the efficiency of supplying an input signal to the amplifying transistor.

Fig. 3FIG. 4FIG. 5## TRANSISTOR AMPLIFIER CIRCUITS WITH STABILIZED LOW CURRENT BIASING

BACKGROUND OF THE INVENTION

1. Field of the Invention

The field of art to which this invention pertains is transistor amplifier circuits with stabilized low current biasing and in particular, to such circuits having a high impedance input.

2. Description of the Prior Art

In a prior art device shown in FIG. 1, an amplifier transistor Q_2 and biasing transistor Q_1 are formed on a common semiconductor substrate, so that both transistors have the same current gain (β) and base-emitter voltage (V_{BE}).

The quiescent collector current of the biasing transistor Q_1 (I_1) is equal to the quiescent collector current of the amplifier transistor Q_2 (I_2) because resistance values R_1 and R_2 are selected equal. I_1 and I_2 are substantially not affected by changes in the transistor's characteristics, namely, changes in V_{BE} , due to temperature variations which are common to both transistors. Consequently, stabilized biasing of the amplifier transistor Q_2 is obtained. The following equations show this to be true:

$$R_1 = R_2$$

β = Current gain of Q_1 and Q_2 ($\beta \gg 1$)

V_{BE} = Base-Emitter voltage of Q_1 and Q_2

$$V_{CC} = R_{L1} \left(I_1 + \frac{I_1}{\beta} + \frac{I_2}{\beta} \right) + R_1 \cdot \frac{I_1}{\beta} + V_{BE} \quad (1) \quad 30$$

$$V_{CC} = R_{L1} \left(I_1 + \frac{I_1}{\beta} + \frac{I_2}{\beta} \right) + R_2 \cdot \frac{I_1}{\beta} + V_{BE} \quad (2)$$

$$(1) - (2) \quad R_1 \cdot \frac{I_1}{\beta} = R_2 \cdot \frac{I_1}{\beta}$$

where R_1 is equal to R_2 , therefore,

$$I_1 = I_2$$

By substituting I_2 for I_1 , Expression (1) becomes as follows:

$$V_{CC} = R_{L1} \left(I_1 + \frac{I_1}{\beta} + \frac{I_1}{\beta} \right) + R_1 \cdot \frac{I_1}{\beta} + V_{BE}$$

$$V_{CC} - V_{BE} = R_{L1} \cdot I_1 + (2R_{L1} + R_1) \cdot \frac{I_1}{\beta} + V_{BE}$$

$$I_1 = \frac{V_{CC} - V_{BE}}{R_{L1}} = \left(\frac{2R_{L1} + R_1}{R_{L1}} \right) \cdot \frac{I_1}{\beta}$$

therefore, for

$$V_{CC} \gg V_{BE}$$

and

$$\left(\frac{2R_{L1} + R_1}{R_{L1}} \right) \cdot \frac{I_1}{\beta} \ll I_1$$

$$I_1 \approx \frac{V_{CC}}{R_{L1}} \quad (3a)$$

Equation (3a) shows that I_1 is independent of V_{BE} . Since the collector current I_1 of the biasing transistor Q_1 has a value equal to the collector current I_2 of the amplifier transistor Q_2 , the power dissipation incurred in the biasing portion will be comparable to that incurred in the amplifier portion. The amplifier of this type usually serves as a high current output stage of a signal channel and therefore this power dissipation in the biasing portion is undesirable.

In an improved prior art device shown in FIG. 2, quiescent collector current I_1 of biasing transistor Q_1 is $1/K_1$ times smaller than quiescent collector current I_2 of amplifier transistor Q_2 . K_1 is larger than 1 and determined by a ratio between resistance values R_1 and R_2 . This ratio is equal to the ratio between resistance values R_3 and R_4 . Therefore, undesired power dissipation incurred in the biasing portion is less than the circuit of Prior Art 1. Further, the collector current I_1 of the biasing transistor Q_1 is substantially not affected by changes in the transistor characteristic due to temperature variations, so the biasing of the amplifier transistor Q_2 is stabilized. The following equations show this to be true:

25

$$\frac{R_1}{R_2} = \frac{R_3}{R_4} = K_1 > 1$$

$$\frac{R_2}{R_4} = \frac{R_1}{R_3} = K_2 > 1$$

β = current gain of Q_1 and Q_2 ($\beta \gg 1$)

$$V_{CC} = R_{L1} \left(I_1 + \frac{I_1}{\beta} + \frac{I_2}{\beta} \right) + R_1 \cdot \frac{I_1}{\beta} + V_{BE} + R_3 \left(I_1 + \frac{I_1}{\beta} \right) \quad (4)$$

$$V_{CC} = R_{L1} \left(I_1 + \frac{I_1}{\beta} + \frac{I_2}{\beta} \right) + R_2 \cdot \frac{I_2}{\beta} + V_{BE} + R_4 \left(I_2 + \frac{I_2}{\beta} \right) \quad (5)$$

$$(4) - (5) \quad R_1 \cdot \frac{I_1}{\beta} + R_3 \left(I_1 + \frac{I_1}{\beta} \right) = R_2 \cdot \frac{I_2}{\beta} + R_4 \left(I_2 + \frac{I_2}{\beta} \right)$$

$$45 \quad \frac{I_2}{I_1} = \frac{R_1 + R_3 (1 + \beta)}{R_2 + R_4 (1 + \beta)}$$

$$= \frac{R_3}{R_1} \cdot \frac{R_3}{R_2} + (1 + \beta)$$

$$= \frac{R_3}{R_1} \cdot \frac{R_3}{R_2} + (1 + \beta)$$

where

$$55 \quad \frac{R_3}{R_4} = K_1$$

and

$$60 \quad \frac{R_1}{R_3} = \frac{R_2}{R_4} = K_2$$

therefore,

65

$$\frac{I_2}{I_1} = K_1$$

$$I_1 = \frac{1}{K_1} I_2 \quad (6)$$

By substituting I_2 for $K_1 \cdot I_1$, expression (4) becomes as follows:

$$V_{CC} = R_{L1} \left(I_1 + \frac{I_1}{\beta} + \frac{K_1}{\beta} \cdot I_1 \right) + R_1 \cdot \frac{I_1}{\beta} + V_{BE} + R_3 + I_1 \left(\frac{I_1}{\beta} \right)$$

$$V_{CC} - V_{BE} = \left\{ R_{L1} \left(1 + \frac{1}{\beta} + \frac{K_1}{\beta} \right) + R_3 \left(1 + \frac{1}{\beta} \right) \right\} + I_1 + R_1 \cdot \frac{I_1}{\beta}$$

where $\beta \gg 1$, K_1 , therefore,

$$V_{CC} - V_{BE} = (R_{L1} + R_3) \cdot I_1 + R_1 \cdot \frac{I_1}{\beta}$$

$$I_1 \approx \frac{V_{CC} - V_{BE}}{R_{L1} + R_3} + \frac{R_1}{R_{L1} + R_3} \cdot \frac{I_1}{\beta}$$

further, for $V_{CC} \gg V_{BE}$ and

$$\frac{R_1}{R_{L1} + R_3} \cdot \frac{I_1}{\beta} \ll I_1$$

$$I_1 \approx \frac{V_{CC}}{R_{L1} + R_3} \quad (6a) \quad 35$$

Equation (6) shows that I_1 equals a constant times I_2 , and equation (6a) shows that I_1 and hence I_2 are independent of V_{BE} .

It should be understood that the resistance value R_4 may be relatively small so as to maintain the high gain of the amplifier which includes the transistor Q_2 . The reason for this is that the gain of a transistor amplifier of the collector follower type is substantially proportioned to the ratio between the collector resistance (R_C) and emitter resistance (R_E) of the transistor, namely R_C/R_E . Accordingly, increased emitter resistance tends to reduce the gain of the amplifier. The small emitter resistance value R_4 , however, provides a low input impedance of the amplifier transistor Q_2 . This results in a disadvantage that a signal circuit connected to the input of the amplifier transistor Q_2 is required to have a low output impedance. Generally, it is a severe requirement for circuits in actual use to provide such a predetermined low output impedance.

SUMMARY OF THE INVENTION

It is an important object of the present invention to provide an improved transistor amplifier circuit with stabilized low current biasing.

It is another object of the present invention to provide such an amplifier circuit which has a substantially high input impedance.

It is a further object of the invention to provide a circuit as described above wherein means are provided to increase the input impedance and further means are included to compensate for current variations due to

temperature changes surrounding the high input impedance means.

It is also an object of the present invention to provide a combination of an emitter follower transistor and a current sink to assure greater efficiency of supplying the input signal to the amplifier.

These and other objects of the invention will become understood from the following description and the associated drawings wherein reference characters are used to designate a preferred embodiment.

BRIEF DESCRIPTION OF THE DRAWINGS

FIG. 1 is a schematic of a prior art device wherein there is undesirable power loss of the biasing transistor and which provides an undesirable low input impedance;

FIG. 2 is a schematic of a prior art device similar to FIG. 1, wherein emitter resistors are also provided. This arrangement has also an undesirably low input impedance;

FIG. 3 is a schematic of a device according to the present invention showing the use of an emitter follower transistor to increase the input impedance of the amplifier;

FIG. 4 is a schematic of a further embodiment of the invention using a fourth transistor to act as a current sink to improve the efficiency of supplying the input signal through the emitter follower transistor to an amplifying transistor; and

FIG. 5 is a schematic of an embodiment of the invention wherein a transistor Q_1 is used as a temperature compensating device.

DESCRIPTION OF THE PREFERRED EMBODIMENTS

This invention relates generally to transistor circuits composed of a plurality of transistors on a common semiconductor chip, and more particularly, to a transistor amplifier operable with a stabilized low current biasing provided by a biasing portion of the integrated circuit.

Referring to FIG. 3 in detail, transistors Q_2 and Q_1 are provided to form an amplifier and a biasing circuit for the amplifier respectively as in the prior art FIGS. 1 and 2. In this circuit, an additional transistor of the emitter follower type, Q_2' is also provided at the input of the transistor Q_2 so as to increase the input impedance of the amplifier. The base and the emitter of the emitter follower transistor Q_2' are connected to a signal input terminal "in," and the base of the transistor Q_2 respectively. Further, in order to compensate for changes in current flowing through the transistors Q_2 and Q_2' due to temperature variations caused by the addition of the transistor Q_2' , a diode D is connected in series with the emitter of the biasing transistor Q_1 . The diode D produces a voltage drop of V_{BE} across its anode and cathode. Resistance values R_1 , R_2 , R_3 , R_4 and R_5 are selected to satisfy the following relations: $R_1/R_2 = K_1'' > 1$, $R_3/R_4 = K_2'' > 1$, $R_3/R_5 = K_3''$.

In operation, input signals to be amplified are applied to the input terminal at the base of the transistor Q_2' and supplied to the base of the transistor Q_2 through the emitter follower transistor Q_2' . The quiescent collector currents I_1 , I_2 and I_2' of the transistors Q_1 , Q_2 and Q_2' have the following interrelations: $I_1 = 1/K_2''$, $I_2 = 1/K_1'' \cdot I_2'$. That is, the collector current I_1 of the biasing transistor Q_1 is $1/K_2''$ times smaller than the collector

current I_2 of the transistor Q_2 and also $1/K_1''$ times smaller than the collector current I_2' of the transistor Q_2' , so that the power dissipation incurred in the biasing portion is less than the Prior Art of FIG. 1. The quiescent collector current I_1 is not affected by changes in the transistor characteristics due to temperature variations and therefore, stabilized biasing of the transistors Q_2 and Q_2' is obtained.

Examples of values of the elements used in FIG. 3 are as follows:

One Example

$$R_1 = 4\text{k}\Omega$$

$$R_2 = 2\text{k}\Omega$$

$$R_3 = 150\Omega$$

$$R_4 = 50\Omega$$

$$R_5 = 450\Omega$$

$$R_{L1} = 8.3\text{k}\Omega$$

$$V_{CC} = 10\text{ v}$$

$$V_{BE} = 0.75\text{ v}$$

$$\beta \approx 100$$

The relationship of I_1 to I_2 and the independence of I_1 and I_2 from temperature variation are shown by equation (10) and (12). As follows:

$$\frac{R_1}{R_2} = K_1' > 1$$

$$\frac{R_3}{R_4} = K_2' > 1$$

$$\frac{R_3}{R_5} = K_3'$$

β = current gain of Q_1 , Q_2 and Q_2' ($\beta \gg 1$)

$$V_{CE} = R_{L1} \left(I_1 + \frac{I_1}{\beta} + \frac{I_2'}{\beta} \right) + R_1 \cdot \frac{I_1}{\beta} + 2V_{BE} + R_3 \cdot \left(I_1 + \frac{I_1}{\beta} \right) \quad (7)$$

$$V_{CE} = R_{L1} \cdot \left(I_1 + \frac{I_1}{\beta} + \frac{I_2'}{\beta} \right) + R_2 \cdot \frac{I_2'}{\beta} + 2V_{BE} + R_1 \cdot \left(I_2 + \frac{I_2}{\beta} \right) \quad (8)$$

(7) - (8)

$$R_1 \cdot \frac{I_1}{\beta} + R_3 \cdot \left(I_1 + \frac{I_1}{\beta} \right) = R_2 \cdot \frac{I_2'}{\beta} + R_1 \cdot \left(I_2 + \frac{I_2}{\beta} \right) \quad (9)$$

$$R_3 \left(1 + \frac{1}{\beta} \right) \cdot I_1 = R_1 \cdot \left(1 + \frac{1}{\beta} \right) \cdot I_2 + \frac{I_2'}{\beta} \cdot R_1 + \frac{I_2}{\beta} \cdot R_2$$

where, $\beta \gg 1$,
therefore,

$$R_3 \cdot I_1 = R_1 \cdot I_2 + R_2 \cdot \frac{I_2'}{\beta} - R_1 \cdot \frac{I_1}{\beta}$$

$$I_2 \doteq \frac{R_3}{R_1} \cdot I_1 - \frac{R_2}{R_1} \cdot \frac{I_2'}{\beta} + \frac{R_1}{R_1} \cdot \frac{I_1}{\beta}$$

further, for

5

$$\frac{R_3}{R_4} = K_2', \quad \frac{R_2}{R_4} \cdot \frac{I_2'}{\beta} \ll I_2$$

and

10

$$\frac{R_1}{R_4} \cdot \frac{I_1}{\beta} \ll I_2$$

$$I_2 \doteq K_2' \cdot I_1$$

15

$$I_1 \doteq \frac{1}{K_2'} \cdot I_2 \quad (10)$$

By substituting I_2 for $K_2' \cdot I_1$, Expression (9) becomes as follows:

$$20 \quad R_1 \cdot \frac{I_1}{\beta} + R_3 \cdot \left(I_1 + \frac{I_1}{\beta} \right) = R_2 \cdot \frac{I_2'}{\beta} + R_4 \cdot \left(1 + \frac{1}{\beta} \right) \cdot K_2' \cdot I_1$$

$$R_1 \cdot \frac{I_1}{\beta} + R_3 \cdot \left(1 + \frac{1}{\beta} \right) \cdot I_1 = R_2 \cdot \frac{I_2'}{\beta} + R_4 \cdot \left(1 + \frac{1}{\beta} \right) \cdot K_2' \cdot I_1$$

where $\beta \gg 1$ and

30

$$K_2' = \frac{R_3}{R_4},$$

therefore,

35

$$R_1 \cdot \frac{I_1}{\beta} + R_3 \cdot I_1 \doteq R_1 \cdot \frac{I_2'}{\beta} + R_3 \cdot I_1$$

$$I_1 \doteq \frac{R_2}{R_1} \cdot I_2'$$

$$\doteq \frac{1}{K_2'} \cdot I_2' \quad (11)$$

Now, base currents

45

$$\frac{I_1}{\beta}, \quad \frac{I_2}{\beta}$$

and

50 55 are negligible as compared with respective collector currents I_1 , I_2 and I_2' in actual operation.

Accordingly, expression (7) substantially becomes as follows:

$$V_{CE} \doteq R_{L1} \cdot I_1 + 2V_{BE} + R_3 \cdot I_1$$

60

$$I_1 \doteq \frac{V_{CE} - 2V_{BE}}{R_{L1} + R_3}$$

therefore, for $V_{CC} \gg 2V_{BE}$,

65

$$I_1 \doteq \frac{V_{CE}}{R_{L1} + R_3} \quad (11a)$$

Equation (11a) shows that I_1 is independent of V_{BE} . FIG. 4 is similar to FIG. 3 where a fourth transistor Q_4 is provided with its collector connected to the emitter of the transistor Q_2' , its emitter connected to ground through a resistor R_6 of relatively small resistance value and its base connected to a junction point between the emitter of the transistor Q_1 and the diode D. All other elements are arranged in the same manner as the circuit of embodiment 1.

This fourth transistor Q_4 operates as a constant current sink with the base biasing voltage maintaining the voltage difference between its base and emitter substantially constant, which biasing voltage is produced at the anode of the diode D and supplied therefrom.

In the circuit of FIG. 3, the resistor R_5 is in parallel with the effective input impedance of the transistor Q_2 , and therefore the input signal is supplied to the base of the transistor Q_2 with a loss due to the presence of R_5 . The efficiency in supply of the input signal is reduced, especially in the case where the resistance R_5 is selected to be close to or less than the value of the input impedance of the transistor Q_2 . On the contrary, the current sink composed of the transistor Q_4 of this circuit can be considered to have a substantially infinite impedance to the input signal supplied to the transistor Q_2 to be amplified therein, so that the input signal can be supplied effectively to the base of the transistor Q_2 without loss.

Also, in this circuit, the quiescent collector currents I_1 , I_2 and I_2' of the transistors Q_1 , Q_2 and Q_2' are present with the same interrelations as the circuit of FIG. 3. Typical values are given by the following:

$$R_1 = 4k\Omega$$

$$R_2 = 2k\Omega$$

$$R_3 = 150\Omega$$

$$R_4 = 50\Omega$$

$$R_6 = 75\Omega$$

$$R_{L1} = 8.3k\Omega$$

$$V_{CC} = 10\text{ v}$$

$$V_{BE} = 0.75\text{ v}$$

$$\beta \approx 100$$

Referring to FIG. 5, an additional biasing transistor Q_1' is connected to the biasing transistor Q_1 with its base-emitter path connected between the collector and base of the transistor Q_1 through the resistance value R_1 . The emitter of the transistor Q_1' is also connected to the ground through a resistor of resistance value R_7 and the collector of the transistor Q_1' is connected to the voltage source. This provides temperature compensation similar to that provided by diode D of FIGS. 3 and 4.

In this case also the current of the biasing portion, that is, the sum of the currents flowing through the transistors Q_1 and Q_1' , is smaller than the quiescent current flowing through the amplifier portion and therefore, the undesirable power dissipation in the biasing portion is reduced. Further, the stabilized biasing for the amplifier portion is obtained in the same manner as the circuits of FIGS. 3 and 4.

The equations which apply to FIG. 5 are as follows:

$$\frac{R_1}{R_2} = \frac{R_7}{R_5} = K_1'' > 1$$

-Continued

$$\frac{R_1}{R_7} = \frac{R_2}{R_5} = K_2'' > 1$$

$$\frac{R_3}{R_4} = K_3'' > 1$$

β = current gain of Q_1 , Q_2 and Q_2' ($\beta >> 1$)

$$10 \quad V_{CC} = R_{L1} \left(I_1 + \frac{I_1'}{\beta} + \frac{I_2'}{\beta} \right) + R_1 \cdot \frac{I_1'}{\beta} + V_{BE} + R_7 \left(I_1' + \frac{I_1'}{\beta} \right) \quad (12)$$

$$15 \quad V_{CC} = R_{L1} \left(I_1 + \frac{I_1'}{\beta} + \frac{I_2'}{\beta} \right) + R_2 \cdot \frac{I_2'}{\beta} + V_{BE} + R_5 \left(I_2' + \frac{I_2'}{\beta} \right) \quad (13)$$

$$20 \quad V_{CC} = R_{L1} \left(I_1 + \frac{I_1'}{\beta} + \frac{I_2'}{\beta} \right) + R_1 \cdot \frac{I_1'}{\beta} = 2V_{BE} + R_3 \left(I_1 + \frac{I_1'}{\beta} \right) \quad (14)$$

$$25 \quad V_{CC} = R_{L1} \left(I_1 + \frac{I_1'}{\beta} + \frac{I_2'}{\beta} \right) + R_2 \cdot \frac{I_2'}{\beta} + 2V_{BE} + R_4 \left(I_2 + \frac{I_2'}{\beta} \right) \quad (15)$$

$$(12) - (13) \quad R_1 \cdot \frac{I_1'}{\beta} + R_7 \left(I_1' + \frac{I_1'}{\beta} \right) = R_2 \cdot \frac{I_2'}{\beta} + R_5 \left(I_2' + \frac{I_2'}{\beta} \right)$$

$$\frac{I_2'}{I_1'} = \frac{R_1 + R_7(1 + \beta)}{R_2 + R_5(1 + \beta)} = \frac{R_7}{R_5} \cdot \frac{\frac{R_1}{R_7} + (1 + \beta)}{\frac{R_2}{R_5} + (1 + \beta)}$$

where,

$$\frac{R_1}{R_7} = \frac{R_2}{R_5} = K_1''$$

and

$$\frac{R_7}{R_5} = K_2''$$

45 therefore,

$$\frac{I_1' + I_2'}{I_1'} = K_2''$$

$$50 \quad (14) - (15) \quad I_1' = \frac{1}{K_1''} - I_2' \quad (16)$$

$$55 \quad R_1 \cdot \frac{I_1'}{\beta} + R_3 \left(I_1 + \frac{I_1'}{\beta} \right) = R_2 \cdot \frac{I_2'}{\beta} + R_4 \left(I_2 + \frac{I_2'}{\beta} \right) \quad (17)$$

By substituting I_1' for

$$\frac{1}{K_1''} - I_2' = \frac{R_2}{R_1} \cdot I_2',$$

expression (17) becomes as follows:

$$65 \quad R_2 \cdot \frac{I_2'}{\beta} + R_3 \left(I_1 + \frac{I_1'}{\beta} \right) = R_2 \cdot \frac{I_2'}{\beta} + R_4 \left(I_2 + \frac{I_2'}{\beta} \right)$$

-Continued

$$\frac{I_2}{I_1} = \frac{R_3}{R_4} = K_3''$$

$$\frac{I_1}{K_3''} = \frac{1}{I_2}$$

Now, base currents

$$\frac{I_1}{\beta}, \frac{I_2}{\beta}, \frac{I_3''}{\beta}$$

and

$$\frac{I_2'}{\beta}$$

are negligible as compared with the respective collector currents I_1 , I_2 , I_1' and I_2' in actual operation.

Accordingly, expressions (12), (13) and (14) substantially become as follows:

$$V_{CC} = R_{L1} \cdot I_1 + V_{BE} + R_7 \cdot I_1$$

25

$$V_{CC} = R_{L1} \cdot I_1 + 2V_{BE} + R_3 \cdot I_1$$

(20) 30

From (20)

$$I_1 (R_{L1} + R_3) = V_{CC} - 2V_{BE}$$

therefore, for $V_{CC} \gg 2V_{BE}$

$$I_1 = \frac{V_{CC}}{R_{L1} + R_3}$$

further, from (19)

$$I_1' = \frac{V_{CC} - V_{BE}}{R_7} = \frac{R_{L1}}{R_7} I_1$$

for $V_{CC} \gg V_{BE}$,

$$I_1' = \frac{V_{CC}}{R_7} = \frac{R_{L1}}{R_7} I_1$$

by substituting I_1 for

$$\frac{V_{CC}}{R_{L1} + R_3}$$

expression (21) becomes as follows:

$$\begin{aligned} I_1' &\stackrel{(18)}{=} \frac{V_{CC}}{R_7} = \frac{R_{L1}}{R_7} \cdot \frac{V_{CC}}{R_{L1} + R_3} \\ &= \frac{R_3}{R_7(R_{L1} + R_3)} V_{CC} \end{aligned}$$

5

Equation (16) shows that I_1' is a constant times smaller than I_2' and equation (18) shows that I_1 is a constant times smaller than I_2 , and equation (20a) shows that I_1 is independent of V_{BE} .

10 It will be apparent to those skilled in the art that many variations and modifications may be made without departing from the spirit and scope of the novel concepts of this invention.

15 We claim as our invention:

1. A transistor amplifier circuit comprising:
a first transistor;

a second transistor connected for supplying current bias to the first transistor;

20 the second transistor having its collector direct current connected to its base through a first resistor;
a third transistor connected in the emitter follower configuration;

a second resistor direct current connected between the collector of the second transistor and the base of said third transistor;

said third transistor being coupled between said second resistor and said first transistor, the ratio of the first resistor to the second resistor being greater than one, the emitters of the first and second transistors being provided with third and fourth resistors, respectively,

the ratio of the third resistor to the fourth resistor being greater than one, and a P-N junction device connected in series with the base-emitter path of said second transistor.

35 (20a) 30 2. A transistor amplifier circuit in accordance with claim 1, wherein said P-N junction comprises a diode coupled in series with the emitter of said second transistor.

3. A transistor amplifier circuit in accordance with claim 1, wherein said P-N junction comprises a fourth transistor having its output connected in parallel with the output of the second transistor, its base coupled to the collector of the second transistor, and its emitter coupled to the base of the second transistor.

45 4. A transistor amplifier circuit in accordance with claim 2, further comprising a fourth transistor having its output terminals coupled in series with the output of said third transistor and its base coupled to a point between said diode and the emitter of said second transistor, whereby said fourth transistor acts as a constant current sink for said third transistor to improve the efficiency of supplying the input signal through said third transistor to the input of said first transistor.
